US00D944213S

(12) **United States Design Patent** (10) Patent No.: **US D944,213 S**
Emami (45) Date of Patent: **** Feb. 22, 2022**

(54) **COMBINED DATA TRANSMISSION CABLE FOR MOBILE DEVICES WITH CASE AND SET OF REPLACEABLE TERMINAL CONNECTORS**

(71) Applicant: **Vonmahlen GmbH**, Luneburg (DE)

(72) Inventor: **Arman Emami**, Berlin (DE)

(**) Term: **15 Years**

(21) Appl. No.: **35/510,520**

(22) Filed: **Apr. 7, 2020**

(80) **Hague Agreement Data**

Int. Filing Date: **Apr. 7, 2020**

Int. Reg. No.: **DM/208064**

Int. Reg. Date: **Apr. 7, 2020**

Int. Reg. Pub. Date: **Oct. 9, 2020**

(51) **LOC (13) Cl. 13-03**

(52) **U.S. Cl.**

USPC **D13/153; D13/108**

CLAIM

The ornamental design for a combined data transmission cable for mobile devices with case and set of replaceable terminal connectors, as shown.

DESCRIPTION

1. Combined data transmission cable for mobile devices with case and set of replaceable terminal connectors
